ELEVATOR

Alva B. See, Greenwich, Conn., assignor to A. B.
See Elevator Company, Inc., a corporation of
Delaware

Application October 19, 1931, Serial No. 569,615

9 Claims. (Cl. 187—73)

In elevator systems, motion is transmitted from a driving motor to the elevator car through a traction drum and cable. Commonly, the cable is secured to the elevator car at one end, is wound around the drum which is located in the overhead structure, and is secured at the opposite end to a counterweight. The weight of the car and the counterweight acting on the cable cause the cable to embrace the drum with such force that the friction between the drum and the cable is sufficient to transmit movement of the drum to the cable. In the upper limit of travel of the elevator car, the counterweight rests upon a bumper at the bottom of the shaftway and the cable sags. However, in high buildings the weight of the cable in this position of the car exerts sufficient force upon the cable to cause such frictional contact of the cable and drum as to maintain the traction of the cable and the car continues to move in response to movements of the drum. Consequently, if through failure of the limit switch at the upper limit of travel of the elevator car, the traction drum continues to rotate, the car will be drawn into the overhead structure, and to provide a means for relieving the force exerted on the drum by the weight of the cable, and thereby preventing the possibility of the car being drawn into the overhead structure by continued movement of the driving motor, after the car has reached the upper limit of its movement, is the object of my invention.

In accordance with my invention, I provide a gripping device which grips the cable, when the elevator car reaches the upper limit of its travel, and relieves the traction drum of the weight of the cable, thereby permitting the traction drum to rotate without movement of the cable and the car. This gripping device consists of a pair of members movable with respect to each other having opposed gripping surfaces between which gripping surfaces the cable of the elevator system is adapted to move. One of the members is adapted to be moved relative to the other into gripping position when the car reaches the upper limit of travel, and securely grip the cable between its gripping surface and the gripping surface of the other member.

When the elevator car reaches the upper limit of its movement, the cables by virtue of their great weight have considerable momentum and the kinetic energy of the moving cables is dissipated suddenly upon the operation of the gripping device to stop and hold the cables. In order to absorb this energy without serious shock to the overhead structure, the gripping device of my invention is constructed to absorb the shock or dissipate the energy incident to stopping the moving cables, without transmitting that energy

as a sudden shock to the overhead structure upon which the gripping device is mounted.

Specifically, one of the gripping members of the gripping device is adapted to move in and relative to the other. This inner member is 65 adapted to be moved relative to the outer member into gripping position by the action of the force of gravity acting thereon, and it moves into and out of gripping position with its gripping surface constantly parallel to the gripping surface 70 of the outer member throughout the limit of its movement. The inner member is held against movement under the force of gravity acting thereon by a latch. This latch is so constructed that it normally rests in the latched position. It is 75 provided with a cam follower which extends into the elevator shaftway and which is adapted to cooperate with a cam on the elevator car for releasing the latch, thereby permitting the inner member to move into gripping position. 80

The two members are resiliently mounted on a base which is adapted to be secured to the overhead structure. This resilient mounting, which may include compression springs, is such that the total energy of the moving cables is absorbed 85 by the resiliency of the mounting. Thus, when the inner member moves into gripping position and the moving cables are gripped between the two members, the members move together against the action of the resilient support and the energy 90 of the moving cable is dissipated in the compression of the resilient members of the support.

The invention will be more clearly understood and the advantages thereof more apparent from the following particular description of the embodiments thereof illustrated in the accompanying drawing in which:

Fig. 1 is a diagrammatic representation of an elevator system utilizing the gripping device of my invention; 100

Fig. 2 is an enlarged side elevation of a gripping device with a guide plate of the support removed; and

Fig. 3 is an enlarged side elevation of a modified form of the gripping device. 105

The elevator system, in connection with which the device of my invention is shown, comprises an elevator car 1 which is adapted to travel in a vertical plane and a driving motor 2 for operating the elevator car. On the shaft 3 of the 110 driving motor, which is mounted on the overhead structure, there is a traction drum 4. Beneath the beam on which the driving motor is mounted, there is mounted an idle drum 5 which is spaced from the drum on the shaft of the driving motor and which cooperates therewith. A cable 6 is secured at one end to the elevator car and is doubly wrapped around the two drums 4 and 5; the other end of the cable extends over the lower drum into the shaftway and is secured 115 120

to a counterweight 7. A second cable 8 is secured at one end to the lower end of the counterweight 7 and passes around a sheave 9 at the bottom of the shaftway, and it is secured at its other end 5 to the bottom of the elevator car. The weight of the car and the counterweight is such that the cable presses against the drums with a force sufficient to cause enough friction between the cable and the drums to transmit any motion of the drums to the cable and through the cable to the elevator car.

At the bottom of the shaft in the plane of travel of the counterweight, there is provided a bumper 10 on which the counterweight rests when the elevator car is in the upper limit of its movement. This bumper serves to absorb the force of the counterweight so as to relieve the cable of that force and lessen the frictional contact between the cable and the driving drum. In large buildings, however, the weight of the cable itself exerts a force upon the cable, which force is adequate to cause the cable to frictionally engage the driving drum with sufficient friction to transmit motion of the driving drum to the elevator car. In such cases when, through failure of the limit switch or failure of some other part of the control mechanism, the driving drum continues to rotate after the elevator car has reached the upper limit of its movement, the car will be drawn up into and crushed against the overhead structure. To avoid this possibility of over travel of the elevator car, I provide a gripping device designated generally by the numeral 11 which is adapted to grip the cable, when the elevator car reaches the upper limit of its travel, and relieve the driving drum of the weight of the cable.

the cable.

The gripping device (shown enlarged in Fig. 2) comprises an outer member 12 and an inner member 13 movable relative thereto. The outer member may be a single block cast with a recess therein and a base 14 on the lower edge thereof. The recess formed in the outer block is adapted to have the cable of the elevator system pass therethrough. On one side of the recess, there is a gripping surface 15 which is parallel to the plane of the cable. On the other side of the recess, there is an inclined surface 16, inclined to the plane of the cable. The inner member or block is of wedge shape having a gripping surface 17 parallel to the plane of the cable and an inclined surface 18 opposite to the gripping surface which inclined surface is complementary to the inclined surface of the outer block. This inner block fits in the recess of the outer block and is adapted to slide along the inclined surface of the outer block, the gripping surface thereof moving towards or from the gripping surface of the outer block through parallel planes.

62 At the upper end of the inner block, there is formed a transverse groove which is adapted to cooperate with a latch which is in the form of a bell crank lever. The bell crank lever, which is pivoted between its ends, has one arm 19 extending into operative relation with the inner block which arm is bent at the end to form a flange 20 which is adapted to enter the groove in the inner block. On the end of the other arm 21 of the bell crank lever there is rotatably mounted a cam follower 22 which extends into the elevator shaftway. This cam follower extends into the path of a cam 23 secured to the elevator car. As the cam, when the elevator car reaches the upper limit of its movement, engages the cam follower on the latch it rotates the latch about its

pivot so as to withdraw the flange 20 from the groove in the inner block. Upon being released from the latch, the inner block, under the force of gravity acting thereon, slides along the inclined plane and engages the cable. Downward movement of the cable draws the block downwardly, firmly clamping the cable between the gripping surfaces of the inner and outer blocks. To facilitate movement of the inner block, anti-friction rollers 24 are inserted between the complementary inclined surfaces of the inner and outer blocks. When the elevator car starts in the downward direction, the frictional contact between the gripping surfaces of the inner block and the cable carries the inner block upwardly with the cables until the latch has been tripped and the flange thereon extends into the groove of the inner block in which position of the inner block, the cables are free to move through the gripping device.

When the inner block comes into play and the cables are gripped between the blocks, the momentum of the moving cables is transmitted to the blocks and the energy of the moving cables must be absorbed. If the outer block is rigidly secured to the overhead structure, the shock incident to the stopping and holding of the moving cables would be very severe, and to avoid this shock and strain upon the overhead structure, the outer block is mounted on the overhead structure through a resilient support which includes a stationary block 24 which may be secured to a part 25 of the overhead structure. Extending from all sides of this stationary block, there are guide plates 26 which embrace the base 14 of the outer block. A plurality of compression springs 27 are placed between the stationary block of the support and the base of the outer block 12. These springs act in opposition to the weight of the cable and are of a strength proportional to the weight of the cables. Thus, when the inner block 13 moves into the gripping position and the cables are securely gripped between the two blocks, the blocks move as a unit against the action of the springs 27, and the momentum of the cables is gradually lessened and the energy dissipated by the compression spring 27.

In Fig. 3 I have shown a modified form of gripping device in which the inner block 13' is secured to the outer block 12' by a parallel linkage. In this instance, the outer block has a groove formed therein the sides of which are parallel to each other and to the plane of the cable. The inner block is rectangular, as seen in elevation, and it is movably connected to the stationary block through two links 28 and 29, one adjacent the top of the outer block and the other adjacent the bottom. The links are mounted parallel to each other and form a parallel linkage so that the inner block moves into and out of gripping position through parallel planes with the gripping surface thereof constantly parallel to the plane of the cable. The operation of this gripping device is identical with that shown in Figs. 1 and 2.

From the above description of my invention, it will be seen that when the elevator car has reached the upper limit of its movement the weight of the cable will be taken up by the structure and not by the driving drum. Under these conditions, the driving drum can continue to rotate without transmitting its movement to the cable as there will not be sufficient friction between the cable and the drum to supply the necessary traction. Consequently, it will be impos-

sible for the elevator car to overrun at the upper limit of its movement and be crushed against the overhead structure.

It is obvious that various changes may be made by those skilled in the art in the details of the gripping device above described within the principle and scope of my invention as expressed in the appended claims.

I claim:

10 1. In an elevator system having an elevator car mounted for travel in a vertical plane, a drum, a counterweight and a cable secured to the car and the counterweight and operatively related to the drum, a cable gripping device for 15 relieving the drum of the weight of the cable in the upper limit of movement of the car comprising a block having a gripping surface adjacent one side of the cable, and a second block cooperating with the first mentioned block and 20 movable with respect thereto into gripping position under the force of gravity acting thereon.

25 2. In an elevator system having an elevator car mounted for travel in a vertical plane, a drum, a counterweight and a cable secured to the car and the counterweight and operatively related to the drum, a cable gripping device for relieving the drum of the weight of the cable in the upper limit of movement of the car comprising a block having a gripping surface adjacent one side of 30 the cable, a second block having a gripping surface on the other side of the cable movable with respect to and cooperating with the first mentioned block and being movable into gripping position under the force of gravity acting thereon, means for restraining the second mentioned block from moving into gripping position, and means adapted to cooperate with the elevator car for releasing said restraining means.

35 3. In an elevator system having an elevator car mounted for travel in a vertical plane, a drum, a counterweight for the car and a cable secured to the car and the counterweight and operatively related to the drum, a cable gripping device for relieving the drum of the weight of the cable in the upper limit of movement of the car comprising a block having a gripping surface adjacent one side of the cable, a second block having a gripping surface on the other side of the cable movable with respect to and cooperating with the first 40 mentioned block and being movable into gripping position under the action of the force of gravity acting thereon, a latch normally restraining the second mentioned block from moving into the gripping position, and means operatively related to the latch and adapted to cooperate with the car to release the movable block.

45 4. In an elevator system having an elevator car mounted for travel in a vertical plane, a drum, a counterweight for the car and a cable secured to the car and the counterweight and operatively related to the drum, a cable gripping device for relieving the drum of the weight of the cable in the upper limit of movement of the car comprising a member adapted to embrace the 50 cable having a gripping surface adjacent one side of and parallel to the plane of the cable and a surface inclined to the plane of the cable on the opposite side of the cable, a second member adapted to move in the space between the inclined 55 surface of the first mentioned member and the gripping surface thereof, said second mentioned member having an inclined surface complemen-

60 tary to and adapted to cooperate with the inclined surface of the first mentioned member and a gripping surface adapted to cooperate with the gripping surface thereof and being movable into gripping position under the force of gravity acting thereon, a latch adapted to hold the second mentioned member against the force of gravity acting thereon, and means adapted to cooperate with the elevator car for tripping the latch.

65 5. In an elevator system having an elevator car mounted for travel in a vertical plane, a drum, a counterweight and a cable secured to the car and the counterweight and operatively related to the drum, a cable gripping device for gripping the cable and relieving the drum of the weight of the cable in the upper limit of movement of the car, the gripping device including means for absorbing the shock incident to the stopping of the moving cable.

70 6. In an elevator system having an elevator car mounted for travel in a vertical plane, a drum, a counterweight and a cable secured to the car and the counterweight and operatively related to the drum, a cable gripping device for gripping the cable and relieving the drum of the weight of the cable in the upper limit of movement of the car, and a resilient support for the gripping device for absorbing the shock incident to the stopping of the moving cable.

75 7. In an elevator system having an elevator car mounted for travel in a vertical plane, a drum, a counterweight and a cable secured to the car and the counterweight and operatively related to the drum, a cable gripping device for gripping the cable and relieving the drum of the weight of the cable in the upper limit of movement of the car, and a support for the gripping device including means for absorbing the shock incident to the stopping of the moving cable.

80 8. In an elevator system having an elevator car mounted for travel in a vertical plane, a drum, a counterweight and a cable secured to the car and the counterweight and operatively related to the drum, a cable gripping device for gripping the cable and relieving the drum of the weight of the cable in the upper limit of movement of the car, a support for the gripping device including a plurality of compression springs acting upon the gripping device and adapted to absorb the shock incident to the stopping of the moving cable.

85 9. In an elevator system having an elevator car mounted for vertical travel, a drum, a counterweight and a cable secured to the car and the counterweight and operatively related to the drum, a cable gripping device for relieving the drum of the weight of the cable in the upper limit of movement of the car comprising a block having a gripping surface adjacent one side of the cable, a second block having a gripping surface on the other side of the cable movable with respect to and cooperating with said first mentioned block and adapted to be moved into gripping position by the force of gravity acting thereon, a support for the gripping device including a plurality of compression springs acting upon the gripping device and adapted to absorb the shock incident to the stopping of the moving cable.
